UNITED STATES PATENT OFFICE.

ASA A. BUSH, OF TITUSVILLE, PENNSYLVANIA.

STILL FOR REFINING PETROLEUM.

SPECIFICATION forming part of Letters Patent No. 269,382, dated December 19, 1882.

Application filed May 10, 1882. (No model.)

To all whom it may concern:

Be it known that I, ASA A. BUSH, of Titusville, in the county of Crawford and State of Pennsylvania, have invented a new and useful Improvement in Stills for Refining Petroleum and the manner of setting the same, of which the following is a specification.

My invention relates principally to those stills known as "cheese-box stills," or those having a round, flat bottom with upright sides, the object being to increase the surface exposed to the fire by increasing the length of flues through which the products of combustion must pass before escaping to the chimney, to reduce the number of fires, and thereby economize in the use of fuel. This I attain by the mode of construction and setting illustrated in the accompanying drawings, in which—

Figure 1 is a plan of the bottom of the interior of the still; Fig. 2, a plan of the walls, furnaces, and flues under the still on line *a b* in Fig. 3; Fig. 3, a vertical section of the still and setting on line *c d* in Fig. 2; Fig. 4, a vertical section of one-fourth of the bottom of the still and setting, on line *e f* in Figs. 1 and 2, as it would appear if extended to a plane surface; and Fig. 5, a vertical cross-section of the same on line *g h* in Fig. 2, (each quadrant of the still and setting being constructed precisely alike.)

In the different drawings the same parts are indicated by the same letters. In Figs. 1 and 2 one quadrant only and in Fig. 3 one side only is lettered, the other parts being precisely alike.

A is the still; B, brick wall inclosing the same and supporting it around the outside; C, walls of turret supporting the still in the center; D D, radial walls from the turret to the outside wall, B. These are built solid from the foundation to the bottom of the still; E E E, concentric partition-walls; H, a depressed ring in the bottom of the still around next the outside. Lying in this depression are the direct and return flues F and G, opening at each end into the fire-space under the still, as hereinafter described. These flues are preferably about eighteen inches in diameter, and the depression H of the same depth, and from three to three and one-half times the width.

I is a grate or furnace, inclosed in brick, and discharging the products of combustion into the direct flue F, the return-flue G opening into the fire-space outside the walls of the furnace I. K is a furnace, the heat from which passes directly against the bottom of the still under the depressed ring H; L L L L, flues connected by the openings M M M at alternate ends of the partition-walls E E E, the first opening being at the opposite end from the furnace K and the opening from the return-flue G. N N are arches dividing the turret into the separate chambers O and P. R is an opening from the flue L into the chamber O, 65 and S an opening from the chamber O to the chamber P. T is a flue leading from the chamber P downward through the chamber O to the smoke-flue V, which leads to the chimney or stack W.

The operation is as follows: When the still A is first filled the fires are started in the furnace I, the heat and products of combustion passing (as indicated by the arrows) through the direct and return flues F and G and the several flues L and openings M and R into the chamber O in the turret; thence through the opening S directly against the bottom of the still; from there through the flues T and smoke-flue V to the stack W, and escaping. This continues until the quantity of oil in the still is so reduced that there is danger of burning the vapor by the extreme heat in the direct and return flues F and G. The fires are then transferred from the furnace I to the furnace K, 85 when the heat and products of combustion pass direct into the flue L, and from thence take the same course as before, except that they do not pass through the flues F and G, and the distillation is completed. As a matter of course, when the furnace I is in use the door of the furnace K must be kept tightly closed, and vice versa.

I claim as my invention—

1. A still for refining petroleum, consisting of the body A, provided with the annular depressed ring H, said depression being provided with two or more sets of direct and return flues, F and G, constructed substantially as described, and for the purposes herein set forth.

2. The combination, with the still A and its

exterior supporting-walls, of two or more fire-boxes, the concentric interior walls, E E E, having openings M M M, forming the series of flues L L L, the fire-box and the flues L L L being connected, as set forth, the wall C forming the chambers O and P, said wall C being provided with openings R, turret, and stack, and connected with flues, as described, whereby the products of combustion are utilized under 5 to the still A, substantially as described.

3. The combination, with the still A, constructed as described, and its exterior supporting-walls, of two or more pairs of fire-boxes, I and K, for alternate use, connected with the flues I I I, substantially as described. 15

ASA A. BUSH.
